UNITED STATES PATENT OFFICE

2,614,591

ATTACHMENT FOR PLANES

Kenneth D. White, Gardenia, Calif.

Application August 9, 1949, Serial No. 109,360

7 Claims. (Cl. 145—5)

1

This invention relates to an attachment for a surfacing plane and it is primarily an object of the invention to provide an attachment of this kind for planing the bottom edge face of a closure member, such as a door, while the same is still hung.

It is also an object of the invention to provide an attachment of this kind including a blade which is positioned to one side of the plane when the attachment is applied and which blade is adapted to be inserted between the bottom edge of the closure member and an adjacent floor surface to shave said bottom edge face of the closure member to free said bottom edge face from sticking to the floor or other surface.

A still further object of the invention is to provide an attachment of this kind embodying means for shaving the bottom edge face of a closure member, such as a door, without removing the same from its hinges or other mounting.

The invention consists in the details of construction and in the combination and arrangement of the several parts of my improved attachment for a surfacing plane whereby certain important advantages are attained, as will herein-after be more fully set forth.

In order that the invention may be better understood, I will now proceed to describe the same with reference to the accompanying drawings, wherein:

Figure 1 is a view in side elevation of an attachment constructed in accordance with an embodiment of the invention, a portion being broken away and an associated plane being indicated by broken lines, a door being indicated in fragment; broken lines, a door being indicated in fragment;

Figure 2 is a view in top plan of the attachment as illustrated in Figure 1, a portion being broken away and the plane being also indicated by broken line and the door shown in fragment;

Figure 3 is a view in front elevation of the attachment with the plane indicated by broken lines and the door in fragment, and

Figure 4 is a vertical sectional view taken substantially on the line 4—4 of Figure 2, looking in the direction of the arrows.

In the accompanying drawings, P denotes diagrammatically a conventional type of plane for wood surfacing having side walls 1, extending from substantially one end of the plane to the other. The attachment as herein embodied is operatively engaged with the forward portion of the plane and when the attachment is in use, the usual blade of the plane is removed.

As illustrated in the accompanying drawings, the attachment comprises two parallel straight

2

members 2 and 3 coextensive in length and of a length to extend from the front end of the plane P, through a substantial portion of the length thereof. These members 2 and 3 are spaced apart a distance greater than the width of the plane P so that when the attachment is applied, the members 2 and 3 will extend along the outer faces of the walls 1 of the plane P, in close proximity thereto.

The members 2 and 3 have their opposite faces flat with their upper and lower faces coplanar and the members 2 and 3 are maintained in desired spaced relation by the rigid cross members 4, resting upon the top edges of the members 2 and 3. The cross members 4 are held in position by the bolts 5 or the like and have end portions 6 extending outwardly beyond the side member 3.

Also bridging the space between the members 2 and 3 at a point substantially midway of the cross members 4, is an upstanding arched rigid cross member 7, resting on the members 2 and 3 and securely held thereto by the bolts 8, or the like. The member 7 also has an end portion 9, extending outwardly beyond the member 3, said extended portion 9 being of a length substantially equal to the length of each of the extended portions 6, of the cross members 4.

Threading through the side member 2, at desired points spaced therealong are the binding or holding screws 11, the inner ends of which bear against the adjacent side wall 1 of the plane P, to effectively secure the attachment on the plane.

The outer face of the side member 3 is provided transversely thereacross with the dovetail guide slots 11, herein disclosed as two in number and located in the end portions of the member 3. Snugly and slidably engaged in the slots 11 are the dovetail keys 12, which stand out from and are formed transversely across the inner side face of an elongated block member or head 14. This member or head 14 is of approximately the same length as the member 3 and is rectangular in cross section with its bottom face a at right angles to the outer face of the member 3. The under or bottom face a of the member or head 14 is longitudinally arcuately bowed downwardly with the high point of such bowed surface midway of the ends of the member or head 14.

Underlying the member or head 14 is a longitudinal marginal portion of a cutting blade B. The blade B is oblong in plan and of a length substantially equal to the length of the member or head 14 and is held to the member or head 14

by the bolts 15. Each of the bolts 15 is freely applied through a hole 16 in the member or head 14 with the lower or free extremity thereof threading into the blade B. The head 17 of the bolt 15 contacts an internal shoulder 18 within the upper portion of the hole 16, so that upon requisite rotation of the bolts 15, the blade B, owing to its inherent resiliency may be adjusted, within certain limitations, toward or from the bottom or under surface *a* of the member or head 14 as may be required.

Freely disposed from above through the extended portions 6 of the members 4 are the elongate screws 19 which thread into the end portions of the member or head 14. Interposed between each extended portion 6 and the adjacent end portion of the member or head 14, is an expansible member 20, herein disclosed as a coil spring of requisite tension encircling a screw 19. These springs 20 constantly urge the member or head 14 downwardly to the limit of its movement in such direction but allows a certain amount of upward movement when required.

Freely disposed from above through the extended portion 9 of the arched member 7 is a screw 21 which threads through the center portion of the member or head 14 with the head 22 of the screw 21 contacting an internal shoulder 23 in the opening 24 through which the screw 21 is freely movable. Contact of the head 22 with the shoulder 23 limits the extent of downward movement of the member or head 14 but such limit of downward movement may be selectively determined by rotation of the screw 21 to adjust the member or head 1 either upwardly or downwardly on the screw 21.

The blade B is of a thickness at all points therealong to be inserted between the lower edge face of a door D or other closure member and the floor or other adjacent surface. The blade B is also of a width, and particularly at the end portions thereof, to extend entirely across and beyond the lower edge face of the door D. Each extremity of the blade B, is upwardly beveled, as at *b*, to provide a cutting edge at each end of the blade B so that the attachment can be employed to effect desired shaving of the under or bottom edge of the door D from one end to the other without the necessity of taking the door D off of its hinges or other mounting.

It is to be noted that the outer end faces of the extensions 6 and 9 are substantially flush or coplanar with the outer face of the member or head 14 so that said extensions 6 and 9 and member or head 14 provide means for limiting the extent of insertion of the blade B beneath the door D and also provide a guide means to assure the tool being maintained in effective working position with respect to the door D.

It is also to be noted that the structure of the attachment is such that it can be applied to the plane P to have the blade B extend forwardly and laterally of the plane as may be desired.

The member 7 is upwardly arched to allow bridging of the central high points of the side walls 1 of the plane P.

While the invention as illustrated in the accompanying drawings and hereinbefore described is set forth as an attachment for a plane, it is believed to be self-evident that it can be used separately and independently of the plane.

When the invention is employed separately or independently of the plane, the members 2 and 3, with, of course, the cross members 4 and 7, constitute a carrier for the blade B. The cross mem-

bers 6 and 7 readily serve as hand grasps to effect the desired stroking of the blade B although, if desired, an additional handle may be employed (not illustrated). As the use of such an extra handle is believed to embody only mechanical expediency, an illustration thereof in the accompanying drawings is believed unnecessary.

I claim:

1. In combination, a hand plane from which the blade is removed, a frame structure formed to receive a portion of the plane, means for securing the structure thereto, a long blade disposed at one side and longitudinally of the plane and projecting laterally from the bottom part of the plane, one end edge of said blade being sharpened and directed upwardly from and above the plane of the bottom face of the hand plane, and means securing the blade to the frame structure, said hand plane constituting a handle.

2. A planing tool of the character stated for attachment to a hand plane body, said planing tool comprising a frame structure, means for securing the structure to the hand plane body for the use of the latter as a handle, an elongate member secured to a side of the frame structure to extend lengthwise of the plane body, said member having a downwardly bowed longitudinal bottom edge, a long longitudinally bowed blade of substantial width having a portion of one longitudinal edge disposed against and corresponding to the curve of said bowed edge, the blade width extending laterally from the adjacent side of the plane body, one transverse edge of the blade being sharpened, means for changing the bow of said blade, and means for moving the blade bodily perpendicularly to its path of working movement without changing its curvature.

3. The invention as stated in claim 2, wherein the said means for changing the bow of said blade comprises a plurality of screws supported for free rotation by said elongate member and projecting through the bowed longitudinal edge of such member, the said portion of the blade being provided with threaded openings in each of which an end of a screw is threadably engaged.

4. The invention as stated in claim 2, wherein the last named means comprises a sliding coupling between the elongate member and the said side of the frame and threaded adjustment screws supported by the frame for free rotation and having threaded connection with the elongate member.

5. A planing tool of the character stated comprising a frame which includes a pair of elongate spaced parallel body members having top edges connected by transverse cross members, means for securing the body of a hand plane between said parallel members whereby the hand plane may be used as a handle, the parallel members extending longitudinally of the hand plane body, an elongate head member disposed longitudinally of the outer face of one of said parallel members, a coupling means between the elongate head and the adjacent longitudinal member by which vertical movement of the head is permitted, said head having a downwardly bowed longitudinal bottom face, a long thin planing blade of substantial width having a portion of one longitudinal edge disposed beneath and against the bowed face of the head, said blade being longitudinally bowed correspondingly to said face and having its width directed outwardly from the adjacent one of the said parallel members, one transverse end edge of the blade being sharpened, means securing the blade to the head, and a coupling means between

5

the head and said cross members by which vertical adjustment of the head and blade may be effected.

6. The invention as set forth in claim 5, wherein each of said cross members has a portion of the end adjacent to the head projected to overlie the head, and said coupling means comprising vertical screws each freely extending through the projecting portion of a cross member and having its lower end threadably engaged in the underlying head.

7. The invention as set forth in claim 5, wherein each of said cross members has a portion of the end adjacent to the head projected to overlie the head, and said coupling means comprising vertical screws each freely extending through the projecting portion of a cross member and having its

5

lower end threadably engaged in the underlying head, and coil spring members each surrounding a screw and interposed between the projecting end of the adjacent cross member and the head and resisting upward movement of the head and blade.
